W. V. Tipping
INVENTOR
BY Victor J. Evans
ATTORNEY

UNITED STATES PATENT OFFICE.

WILLIAM V. TIPPING, OF MARSHALL, MISSOURI.

DESIGN FOR A MONUMENT.

Application filed October 15, 1923. Serial No. 7,505. Term of patent 14 years.

To all whom it may concern:

Be it known that I, WILLIAM V. TIPPING, a citizen of the United States of America, residing at Marshall, in the county of Saline and State of Missouri, have invented a new, original, and ornamental Design for a Monument, of which the following is a specification, reference being had to the accompanying drawings, forming a part hereof.

The figure is a perspective view showing my new, original and ornamental design for a monument.

I claim:—

The ornamental design for a monument as shown.

WILLIAM V. TIPPING.

Witnesses:

ANNA J. BOOTH,
W. T. BELLAMY.
